FRUIT AND VEGETABLE PEELER

Ralph V. Grayson, Atlanta, Ga.

Application October 19, 1931, Serial No. 569,777

10 Claims. (Cl. 146—43)

This invention relates to machines for peeling fruits and vegetables, and more particularly to machines for peeling oranges, grape fruits and the like but adapted to peel other articles having a substantially spherical shape.

The object of the invention is to provide a device capable of operating on a plurality of objects applied to it in continuous procession, to effectively peel the same in a rapid and highly efficient manner and discharge the peeled fruits.

Further objects will more particularly appear in the course of the detailed description of the invention.

The invention consists in the novel construction, arrangement and combinations of parts hereinafter more particularly described and claimed.

Three sheets of drawings accompany this specification, being largely diagrammatic in character. Like reference characters indicate like parts throughout the description.

In the drawings:

Fig. 1 is a front elevation of the improved machine.

Fig. 2 is a plan of the machine.

Fig. 3 is a vertical transverse cross-section taken on the line 3—3 of Fig. 1.

Fig. 4 is an end elevation.

Fig. 5 is a fragmentary cross section on line 5—5 of Fig. 1 showing the drive mechanism for the feed and pressure rollers.

Fig. 6 is a longitudinal cross-section taken on the line 6—6 of Fig. 2, showing the construction of the pressure roller.

Fig. 7 is a transverse cross section taken on line 7—7 of Fig. 6.

Fig. 8 is a perspective of one unit of the pressure roller.

Fig. 9 is a plan projection of the lines determined by the fruit contacting and propelling elements on the propelling roller.

Fig. 10 is a perspective of the entire machine.

Referring to the drawings, the improved peeling device may be conveniently mounted on a base 1, and consists essentially of four rollers identified by 2, 3, 4 and 5, arranged with their axes parallel, two of the said rollers 2 and 3 being arranged with their perimeters in a substantially common horizontal plane and slightly spaced apart so as to form a supporting trough for the fruit or other objects to be peeled. The third or knife roller 4 is arranged above and intermediate the rollers 2 and 3. The fourth or what may be termed the peeling gauge roller 5, is arranged adjustably under the knife roller

4. Roller 2 is a propelling roller and is provided with a plurality of radially disposed striker and guiding members 15, which members are arranged in a staggered manner, following, however, a substantially spiral course from one end of the 60 roller to the other. The width of the path defined by the adjacent convolutions of said striker members is the same throughout.

By referring to Fig. 9, it will be noted that the path of the radially disposed striker members 15 65 is such as to propel the fruit backwards a short distance and forwardly a greater distance during each revolution of the propelling roller and these relative backward and forward motions are preferably related in the ratio of 1 to 2.

The upper or peeler roller 4 is provided with a peripheral spiral knife 14, and may be conveniently mounted upon spindle 5' supported in suitable bearings upon which spindle will be secured driver pulley 6, which will be driven from a 75 motor (not shown).

The supporting roller 3 is specially constructed to provide for automatic adjustment to accommodate a substantial range of sizes in the fruit and also rather pronounced variations in the shape 80 of the individual fruits. To this end it consists of a plurality of roller elements 7, each of which is preferably provided with longitudinally disposed peripheral corrugations 8 and an axial orifice 9. These roller units are assembled on a 85 spindle 10 on which is spirally wound a spiral spring 11 which provides a flexible resilient support for each of these independent roller elements.

The gauge roller 5 for regulating the depth 90 of the peeling to be cut by knife roller 4, is an idler which may be conveniently mounted on a spindle 12 horizontally adjustable in slotted brackets 13 and held in adjusted position as by wing nuts 16.

The rollers 2 and 3 are fixedly mounted on shafts 17 and 18 respectively, on which latter are pivoted frame members 19 in which are journals for the shaft 17, and the stub drive shaft 20. The stub shaft 20 carries two gears 21, 22, which mesh with and drive gears 23 and 24 mounted respectively on shafts 18 and 17. The stub shaft 20 is also provided with a spiral gear 25 which meshes with a worm 26, on main drive shaft 27, which is rotatably mounted in bracket 28, pivotally mounted on one of the frame members 19, and is driven from any suitable source of power (not shown).

The frame members 19 are adjustable angularly with respect to their pivot shaft 18, by means 110

of cams 29 which are mounted on shaft 30 rotatable by handle 31.

By the arrangement illustrated, it will be noted that the propelling rollers 2 and 3 are rotated in the same direction so that the orange or other object placed between these propelling motors will be rapidly rotated by the same on a substantially horizontal axis parallel with those of the propelling rollers. Simultaneously, the striker members 15 upon roller 3 will successively strike opposite vertical sides of the orange and spin or rotate the same in opposite directions successively on an axis substantially at right angles to that of the axes of the rollers.

15 It will thus be apparent that the object to be peeled is given a rapid compound rotary movement, while at the same time it is advanced from one end of this propelling roller to the other by reason of the substantially spiral course of the 20 striker members, and that throughout its passage over the propelling rollers the rapidly rotating spiral knife will continually scarf and remove the skins or rind from the fruit.

25 Various modifications and mechanical adjustments by means of which the relative spacing of the rollers can be determined for various sizes of fruits and the like will readily suggest themselves to those skilled in the art, but within the scope of the present invention, as claimed.

30 What I claim is:

1. A peeler comprising a plurality of rollers having substantially parallel axes, two of said rollers arranged in spaced relation in a substantially horizontal plane to constitute propellers and a third roller arranged above and substantially medial of said propellers; knife means on said third roller; means on one of said propeller rollers adapted to advance an object axially, and means for rotating said rollers.

35 2. The combination of claim 1 in which the knife means is arranged spirally on its roller.

3. The combination of claim 1 in which the

means for moving the object axially of the propeller rollers comprises peripherally disposed contact means spirally arranged on one of said propeller rollers.

4. The combination of claim 1 in which the means for moving the object axially of the propeller rollers comprises peripherally disposed contact members arranged in a zig-zag manner following a generally spiral course whereby an object will be alternately propelled in opposite axial directions but predominantly in one axial direction.

5. In a peeler, in combination, means for rotating an object continuously on one axis of the object in one direction, means for rotating the object on an axis of the object perpendicularly to that first mentioned in opposite directions successively, and means for scoring the object during its rotation.

6. In a peeler, in combination, means for progressing a plurality of objects in a determined direction, means for simultaneously rotating said objects on a plurality of angularly disposed axes passing through said objects, means for successively reversing the direction of rotation on certain axes and means for scoring the objects continuously during said progression.

7. The structure of claim 1, in which one of said propeller rollers includes a resiliently supported fruit contacting element.

8. In a fruit peeling machine a fruit supporting roller comprising a shaft, a spiral spring spirally wound on said shaft, and a plurality of roller elements supported on said shaft and spring.

9. The structure of claim 1, with a guard roller adjustably positioned adjacent the knife roller to regulate the depth of the peeling cut.

10. The structure of claim 1, with means for adjusting one of the propeller rollers toward and away from the knife roller.

RALPH V. GRAYSON.
